UNITED STATES PATENT OFFICE

WILLIAM DE BACK, OF SAN LEANDRO, CALIFORNIA, ASSIGNOR TO SPRAGUE-SELLS CORPORATION, OF HOPESTON, ILLINOIS, A CORPORATION OF DELAWARE

COOKING APPARATUS

Application filed November 24, 1926. Serial No. 150,519.

My invention relates to apparatus for processing packaged goods and particularly to cookers adapted to handle filled cans of food material.

5 An object of the invention is the provision of a cooking apparatus comprising separate cooking drums with improved conveying means for enabling the drums to be most efficiently utilized either separately or in combination.

10 Another object of the invention is the provision of improved transfer means for shunting the cans from the supply track to the various feed tracks.

15 Another object of my invention is the provision of a cooking apparatus in which the cans of food material may be cooked for any desired length of time.

20 Other objects of the invention will be set forth in the description of the preferred embodiment of my invention which is illustrated in the drawings forming part of the specification. It is understood that I do not limit myself to the showing made by the said description and drawings, as I may adopt variations of my preferred embodiment within the scope of my invention as set forth in the claims.

25 Referring to the drawings:

30 Figures 1^a and 1^b together constitute a plan view of my cooking apparatus; Figures 2^a and 2^b constitute a side elevation of the same. Portions of both figures are omitted to reduce their length.

35 Figure 3 is a left end elevation of the cooking apparatus.

Figure 4 is a plan view of the elevator or transfer mechanism shown at the left end of Figure 1^a on a smaller scale.

40 Figure 5 is a vertical sectional view thru the feed tracks and conveyor. The plane of section is indicated by the line 5—5 of Figure 1^a.

45 In broadly descriptive terms, the apparatus of my invention comprises a plurality of drums in which suitable conveying mechanism is included to carry the packages therethru. The drums are preferably in axial alinement and separate means is provided for driving the conveyor in each drum at selected

speeds. Each of the drums is joined by a connecting track to the one next in line so that if desired, cans may pass consecutively thru all the drums. A supply track is provided for conducting the cans to the apparatus and a feed track beginning near the end of the supply track conducts the cans to each of the connecting tracks. Means are provided for shunting cans from the supply track to the selected feed track, so that the cans may be 55 passed thru all of the drums, or thru the second and successive drums, or thru the third and successive drums in accordance with the length of time which it is desired to cook the material in the cans. By making the 60 drums in each apparatus of different lengths, or by varying the speed of the drum conveyors, or both, a proper selection of drums permits a considerable latitude in determining the length of time during which the cans 65 are in the cooking chambers. These values are so selected as to give the practically desirable length of cook for different products to be handled, such as cherries, apricots, peaches, pears, etc., each of which requires a 70 different cooking period. Preferably the last drum in the series of drums is a cooler in which the hot cans are cooled off to stop the 75 cooking process.

More particularly my device comprises a 80 series of axially alined drums 2, 3, 4 and 5. Any number of drums may be utilized but three cooking drums and one cooling drum will be found satisfactory for a wide range of work. Each of the drums contains a spiral 85 track 7, around which the cans 8 in the drum are moved on the conveyor reel 9. This mechanism is well known in the art and need not be explained in detail here. The shaft 11 on which the reel for the drum 2 is mounted terminates in a gear 12 on the outside of the drum and this gear is connected thru a suitable gear 13 with the driving gear 14 on the shaft of the motor 16 mounted on a suitable bracket 17 at one end of the drum. For 90 drums 2 and 4 the reel driving means is disposed at the discharge end of the drum, but for drums 3 and 5 the driving means is arranged at the receiving end of the drum. This is done because it is desired to have the reels 95 100

revolve in opposite directions in adjacent drums and practical considerations of manufacture also make it advisable.

The first drum 2 of the series is provided with the receiving chute 18 at one end on one side and at the opposite end on the opposite side with the discharge chute 19 joined by the connecting track 21 with the receiving chute 22 of the second drum 3. The second drum at the opposite end and side is provided with the discharge chute 24 joined by the connecting track 26 with the receiving chute 27 of the third drum 4. In a similar way the third drum 4 is joined to the cooler drum 5 by the connecting track 28. Cans emerge from the cooling drum thru the discharge chute 29 upon a suitable table or conveyor, not shown. Each of the cooking drums is provided with steam thru the valved pipe 31 connected at one end to any suitable source and at the other to the manifold pipe 32 connected into the bottom of the drum thru a plurality of pipes 33. A valved pipe 34 connected to a suitable water supply is also connected into the bottom of the drum so that the desired quantity of water may be admitted thereto. The drums may be emptied thru the valves 36.

Disposed on the top of the first two drums 30 on suitable legs 38 is a structure formed largely of angle irons and providing guideways 39 and 41 in which the two endless chains 42 may run. The chains pass over sprockets 43 arranged on a shaft 44 disposed near the discharge end of the second drum 3 and which is driven by the motor 46 thru the reduction gearing 47. Adjacent the receiving end of the first drum, the chains pass over sprockets 48 and 49 and around the sprockets 51 near the floor and journaled on the shaft 52 mounted in the bracket arms 53. The guideways 39 are turned downwardly for a short distance over the pulleys 48 and are continued in the guideways 54 which extend downwardly, close to the sprockets 51. The under-reach of the chains between the sprockets 49 and 51 are also confined in guideways 56. The two chains 42 are connected at suitable intervals by pieces of pipe 57 journaled on studs 58 projecting from the chains so that the pipe may turn freely.

Extending longitudinally between and somewhat below the guideways 39 are angle pieces 61 and 62 supported on cross-pieces 63 extending between the legs 38. These angle pieces form feed tracks, one of which, 64, is very short and discharges by means of the curved extension 66 into the receiving chute 18 of the first drum 2. Another track-way 67 discharges thru the extension 68 into the connecting track 26 between the second and third drums 3 and 4 respectively. A third feed track 69 discharges thru the extension 71 into the connecting track 21 joining the first and second drums 2 and 3 re-

spectively. The proportions of parts are such that cans in the feed tracks are pushed along by the cross-pipes 57 when the chains 42 are in motion. Supported by braces 72 on the brackets 53 is a supply track 73 sloping downwardly from a source of filled cans, so that cans roll down it by gravity. Means are provided for shunting or carrying cans from the supply track to a selected feed track. Extending between the plates 74 which support the guideways 54 and 56 is a bar 76 at the center of which is pivoted a channel or transfer track 77 by means of the pivot pin 78, so that the upper end of the transfer track may be swung into register with any one of the three feed tracks 64, 67 and 69. The transfer track is moved to selected position by means of a rod 81 pivoted thereto and terminating in a suitable handle 82. The rod 81 passes thru a fixed sleeve 83 and a thumb screw 84 in the sleeve provides means for fixing the rod and therefore the transfer track in selected position.

The spacing of the cross-pipes 57 of the conveyor chains is slightly greater than the diameter of the cans, and as cans roll off of the end of the supply track they are caught between the cross-pipes and carried upwardly in the transfer track and on to the aligned feed track and then along the feed track to the end thereof, finally being discharged into the first drum or the connecting track between the first and second drums, or the connecting track between the second and third drums, as the case may be. From the above it will be clear that if the longest possible period of cooking is desired, the transfer track will be aligned with the trackway 64 so that the cans are fed into the receiving chute 18 of the first drum. The cans will then pass thru each of the drums in turn, finally emerging from the cooler. If all of the drums are used, a considerable variation in the time of cooking may be secured by varying the speed of the conveyor reels in the drums. By aligning the transfer track with the feed track 69, the cans will skip the first drum and enter the connecting track between the first and second drums passing into the second drum and thence thru the remaining drums. The cutting out of the first drum effects a change in the cooking time, but by varying the speed of the conveyor reels in the second and succeeding drums, a wide variation in cooking time for this grouping of drums may be secured. In the same way, only the third drum may be utilized by aligning the transfer track with the feed track 67, so that the cans are discharged into the connecting track between the second and third drums. When one of the drums is not being used, steam may be shut off from it and the driving means for the conveyor reel shut down. My cooking apparatus is thus capable of efficient operation, since only those por-

tions in actual use need be kept at cooking temperature and in operation.

I claim:

1. In an apparatus for treating packaged goods, a plurality of drums, means connecting adjacent drums for conducting the packages from one drum to the other, a supply track for conducting the packages to the apparatus, a feed track extending from adjacent the supply track to each drum, and means for shunting packages from the supply track to a selected feed track. 70
2. In an apparatus for treating packaged goods, a plurality of drums, a supply track for conducting the packages to the apparatus, connecting tracks extending respectively from the discharge ends of the first and second drums to the receiving ends of the second and third drums, a plurality of feed tracks 75 discharging respectively into the connecting tracks and the first drum, and means for shunting packages from the supply track to a selected feed track. 80
3. In an apparatus for treating packaged goods, a plurality of drums, a supply track for conducting the packages to the apparatus, a feed track extending to each drum and having their receiving ends side by side, a transfer track for connecting the supply track to a selected feed track, and means for propelling the packages along the transfer track. 85
4. In an apparatus for treating packaged goods, a plurality of drums, a supply track for conducting the packages to the apparatus, a feed track extending to each drum and having their receiving ends side by side, a transfer track for connecting the supply track to a selected feed track, an endless chain arranged on each side of the transfer track, 90 and means to engage the packages on the transfer track carried by the chains. 95
5. In an apparatus for treating packaged goods, a plurality of drums, a supply track for conducting the packages to the apparatus, a feed track extending to each drum and having their receiving ends side by side, a transfer track for connecting the supply track to a selected feed track, an endless chain arranged on each side of the transfer track, 100 and bars carried by the chains and extending across the transfer track in all of its positions to engage the packages thereon. 105
6. In an apparatus for treating packaged goods, a plurality of drums, a supply track for conducting the packages to the apparatus, a feed track extending to each drum and having their receiving ends side by side, a transfer track for connecting the supply track to a selected feed track, an endless chain arranged on each side of the transfer track and extending along a portion of the feed tracks, and means carried by the chains to engage the packages on the transfer track and portions of the feed tracks. 110
7. In an apparatus for treating packaged goods, a plurality of drums, a supply track for conducting the packages to the apparatus, a feed track extending to each drum and having their receiving ends side by side, a transfer track for connecting the supply track to a selected feed track, an endless chain arranged on each side of the transfer track and the group of feed tracks, and means carried by the chains to engage the packages on the transfer and feed tracks. 115
8. In an apparatus for treating packaged goods, a plurality of drums, a supply track for conducting the packages to the apparatus, connecting tracks extending respectively from the discharge ends of the first and second drums to the receiving ends of the second and third drums, a plurality of feed tracks extending respectively into proximity to the connecting tracks and the receiving end of the first drum, each feed track having a downwardly slanting extension discharging respectively into the connecting tracks and the first drum, a transfer track for shunting packages from the supply track to a selected feed track, and unitary means for propelling the packages from the supply track over the transfer and feed tracks. 120
9. In an apparatus for treating packaged goods, a plurality of drums, a supply track for conducting the packages to the apparatus, connecting tracks extending respectively from the discharge ends of the first and second drums to the receiving ends of the second and third drums, a plurality of feed tracks extending respectively into proximity to the connecting tracks and the receiving end of the first drum, each feed track having a downwardly slanting extension discharging respectively into the connecting tracks and the first drum, means for shunting packages from the supply track to a selected feed track, and means for propelling the packages over the feed track. 125
10. In an apparatus for treating packaged goods, a plurality of drums, a supply track for conducting the packages to the apparatus, connecting tracks extending respectively from the discharge ends of the first and second drums to the receiving ends of the second and third drums, a plurality of feed tracks extending respectively into proximity to the connecting tracks and the receiving end of the first drum, each feed track having a downwardly slanting extension discharging respectively into the connecting tracks and the first drum, a transfer track for shunting packages from the supply track to a selected feed track, and an endless chain arranged on each side of the transfer track and the group of feed tracks, and means carried by the chains to engage the packages on the transfer and feed tracks. 130

goods, a plurality of drums, a supply track for conducting the packages to the apparatus, a feed track extending to each drum, means for shunting packages from the supply track to a selected feed track, a conveyor in each drum for carrying the packages, and means for independently driving each drum conveyor means.

12. In an apparatus for treating packaged goods, a plurality of drums, a supply track for conducting the packages to the apparatus, connecting tracks extending respectively from the discharge ends of the first and second drums to the receiving ends of the second and third drums, a plurality of feed tracks discharging respectively into the connecting tracks and the first drum, means for shunting packages from the supply track to a selected feed track, a conveyor in each drum for carrying the packages, and means for independently driving each drum conveyor means.

13. In an apparatus for treating packaged goods, a plurality of drums, means connecting adjacent drums for conducting packages from one drum to the other, supply means for conducting the packages to the apparatus, a feed track extending from adjacent the supply means to each drum, and means for shunting packages from the supply means to a selected feed track.

In testimony whereof, I have hereunto set my hand.

WILLIAM DE BACK.
